UNITED STATES PATENT OFFICE.

JOHN T. FITZSIMMONS, OF DAYTON, OHIO, ASSIGNOR TO THE DAYTON ENGINEERING LABORATORIES COMPANY, OF DAYTON, OHIO, A CORPORATION OF OHIO.

IGNITION SYSTEM.

Application filed June 20, 1921. Serial No. 478,786.

To all whom it may concern:

Be it known that I, JOHN T. FITZSIMMONS, a citizen of the United States of America, residing at Dayton, county of Montgomery, 5 State of Ohio, have invented certain new and useful Improvements in Ignition Systems, of which the following is a full, clear, and exact description.

This invention relates to ignition apparatus for supplying electrical ignition to the cylinders of an internal combustion engine and to an auxiliary appliance such as a liquid fuel burner for heating the engine intake.

15 One of the objects of the invention is to provide an ignition system including a battery ignition coil and timer for engine ignition and another ignition device for the auxiliary appliance which is constructed to 20 be controlled by the engine ignition timer without change thereto and without interfering with the engine ignition; and it is an object to cut down the current consumption by the other ignition device as the speed 25 of the engine increases.

Another object is to provide an ignition unit for the auxiliary appliance so constructed that it may be installed with the usual engine ignition equipment by making 30 certain connections therewith but without changing the equipment.

In this connection it is a further object to provide a unitary structure including an ignition coil for the auxiliary equipment and 35 control devices for said coil which may be connected onto the regular engine ignition system.

Other and further objects and advantages 40 of the present invention will be apparent from the following description, reference being had to the accompanying drawings, wherein a preferred embodiment of the present invention is clearly shown.

In the drawings:

45 Fig. 1 is a wiring diagram of the engine and auxiliary ignition system; and

Figs. 2, 3 and 4 are sectional, top and side views, respectively, of an ignition unit for the auxiliary appliance.

50 Referring to Fig. 1, a grounded battery 20 is connected by wire 21, ignition switch 22, wire 23, ignition resistance 24 with engine ignition coil 25 having primary 26 and secondary 27, and with grounded timer 55 28 having contacts 29 and 30 intermittently

separated by the operation of the engine. 31 is a condenser in shunt with contacts 29, 30. Distributor 32 connects in recurrent sequence the secondary 27 with engine plugs 33.

The ignition unit for the auxiliary appliance is designated as a whole by numeral 40 and includes an ignition coil 41 having core 42 primary 43 and secondary 44 grounded at one end on primary 43 and connected to a grounded spark plug 45 of the auxiliary 60 appliance such as a liquid fuel burner. A magnetic yoke 46 is magnetically related to core 42 and supports a core 47 and a leaf spring conducting blade 48. Magnet winding 49 surrounds core 47 and is connected 65 to terminal 50 and wire 51 with wire 23, and by terminal 52 and wire 53 with primary 54 engine ignition circuit between primary 26 and timer contact 29.

Blade 48 supports vibrator armature 55 75 carrying a stop 56 for engaging the free end of blade 48, and blade 48 supports vibrator contact 57 normally held by blade 48 against contact 58 supported by adjusting screw 59 connected by wire 60 with primary 80 43. Primary 43 is connected by wire 61 with terminal 50. Condenser 62 is connected in parallel with contacts 57, 58.

When the switch 22 is closed the engine ignition devices 25, 28 and 32 operate in 85 usual manner to provide ignition for the plugs 33. While the timer contacts 29, 30 are open the vibrator elements 48, 55 and 56 cooperate with the coil 41 intermittently to energize coil 41 to supply ignition at plug 90 45. But when contacts 29, 30 are closed the holding coil 49 is energized by current from battery 20, so that the instant contacts 57, 58 are separated armature 55 will be held down in contact separating position until the timer 95 contacts 29, 30 open.

At low engine speeds the timer contact open period will be greater than at higher speeds hence the vibrator will operate longer at low engine speeds. This feature is 100 advantageous where it is desired to furnish ignition to a liquid fuel burner for heating the engine intake manifold. Such burners generally require more ignition when starting cold than when warmed up and the engine is running on its own power. Therefore during the cranking of the engine the duration of the periodically occurring spark showers produced by unit 40 will be relatively great to supply this need for increased 105 110

burner ignition. But during the operation of the burner while the engine is running, such burners do not generally require much ignition to keep them lighted. The periodicity of armature 55 is such that at high engine speeds it can vibrate only once or twice during the closed period of the timer contacts, thereby causing one or two sparks to occur in recurrent succession at plug 45. 10 Such ignition is all that is required for normal burner operation. Hence the present invention tends to use up battery current only as needed.

Figs. 2, 3 and 4 show an embodiment of 15 unit 40 in a unitary structure. Housing tube 70 resting on base 71 supports brackets 72 and 73 supporting coil 41, the core 42 of which projects through coil housing cover 74 which rests on tube 70 and supports 20 yoke 46. Yoke 46 is spaced magnetically from the core 42 by gap 75 and has ears 76 and 77 supporting the housing of condenser 62. The condenser 62 is grounded on cover 74 and the other terminal 62^a is connected 25 with wire 60 to a clip 78 and thence to a plate 79 supporting the screw 59. Plate 79 is mounted upon but insulated from a post 80 extending from cover 74.

For grounding the contact 57 and condenser 62 on the same ground as battery 20 and timer 28, terminal 81 is provided. Wires 49^a and 49^b connect coil 49 with terminals 50 and 52, respectively.

Post 81 rising from cover 74 has a threaded 35 end cooperating with nut 82 to retain in place cover 83 for the vibrator, condenser and holding coil.

To install the unit 40 it is only necessary to connect terminal 50 with the battery terminal 40 of the engine ignition coil, the terminal 52 with the timer terminal of the ignition coil, the terminal 81 with ground (the engine or automobile frame) and the high tension terminal 44^a of coil 41 with the auxiliary spark plug such as the plug at the liquid fuel burner.

In order to quiet the action of the vibrator rubber cushions 56^a and 47^a are provided, it being understood that cushion 56^a will 50 strike spring blade 48 before armature 55 strikes cushion 47^a.

While the form of mechanism herein shown and described constitutes a preferred 55 form of embodiment of the invention, it is to be understood that other forms might be adopted, all coming within the scope of the claims which follow.

What I claim is as follows:

1. In an ignition system for internal combustion engines, the combination with a current source; of one or more engine spark plugs; ignition means for said engine plugs including an ignition coil and a timer; another spark plug for separate ignition purposes; and other ignition means electrically 60 controlled by said timer for supplying ignition periodically for said other plug.

2. In an ignition system for internal combustion engines, the combination with a current source; of one or more engine spark 70 plugs; ignition means for said engine plugs including an ignition coil and a timer; another spark plug for other ignition purposes; a second ignition coil; and electrical means controlled by the position of the timer 75 contacts for causing the second coil periodically to supply ignition for said other plug.

3. In an ignition system for internal combustion engines, the combination with a current source; of an ignition coil for engine 80 ignition; an ignition coil for other ignition purposes; a vibrator intermittently to interrupt the circuit between the second coil and the current source; a timer periodically to connect the first coil with the current 85 source; and means under the control of the timer for rendering the vibrator periodically inoperative.

4. In an ignition system for internal combustion engines, the combination with a current source; of an ignition coil for engine 90 ignition; an ignition coil for other ignition purposes; a vibrator intermittently to interrupt the circuit between the second coil and the current source; a timer periodically to 95 connect the first coil with the current source; and means under the control of the timer for rendering the vibrator periodically inoperative, when the timer connects the first ignition coil with the current source. 100

5. In an ignition system for internal combustion engines, the combination with a current source; of an ignition coil for engine ignition; an ignition coil for other ignition 105 purposes; a vibrator intermittently to interrupt the circuit between the second coil and the current source; a timer periodically to connect the first coil with the current source; and an electromagnet under the control of the timer for arresting the movement of the vibrator. 110

6. In an ignition system for internal combustion engines, the combination with a current source; of an ignition coil for engine ignition; an ignition coil for other ignition 115 purposes; a vibrator intermittently to interrupt the circuit between the second coil and the current source; a timer periodically to connect the first coil with the current source; and an electromagnet rendered operative to arrest the movement of the vibrator when the timer connects the first coil with the current source. 120

7. In an ignition system for internal combustion engines, the combination with a current source; of an ignition coil for engine ignition; an ignition coil for other ignition 125 purposes; a vibrator controller for said second coil including cooperating contacts and an armature for intermittently effecting sep- 130

- aration of said contacts; a timer periodically to connect the first coil with the current source; and an electromagnet connected with said current source by the closing of the contacts of said timer, and cooperating with said vibrator armature to hold the same in contact separating position.
8. In an ignition system for internal combustion engines, the combination with a current source; of an ignition coil for engine ignition; an ignition coil for other ignition purposes; a vibrator controller for said second coil including cooperating contacts and an armature magnetically related to the core of said second ignition coil for intermittently effecting separation of said contacts; a timer periodically to connect the first coil with the current source; and an electromagnet connected with said current source by the closing of the contacts of said timer, and cooperating with said vibrator armature to hold the same in contact separating position, said electromagnet having a core magnetically related to the core of said second ignition coil.
9. In an ignition system for internal combustion engines, the combination with a current source; of an engine ignition coil; an engine operated circuit closer for intermittently connecting the coil and current source; a second ignition coil; a second circuit closer mechanically separate from said first circuit closer for connecting the second coil and current source; and means under control of the first circuit closer for modifying the action of the second circuit closer.
10. In an ignition system for internal combustion engines, the combination with a current source; of an engine ignition coil; an engine operated circuit closer for intermittently connecting the coil and current source; a second ignition coil; a second circuit closer for connecting the second coil and current source; and electrically operated means under control of the first circuit closer for rendering the second circuit closer inoperative.
11. In an ignition system for internal combustion engines, the combination with a current source; of an engine ignition coil; an engine operated timer having a pair of contacts for intermittently connecting the coil and current source; a second ignition coil; a second circuit closer for connecting
- the second coil and current source; and electrical means rendered operative by the closing of said contacts for rendering the second circuit closer inoperative.
12. In an ignition system for internal combustion engines, the combination with a current source; of an engine ignition coil; an engine operated timer having a pair of contacts for intermittently connecting the coil and current source; other ignition apparatus including a second coil; and electrical means rendered operative by the closing of said contacts for rendering said other apparatus inoperative.
13. Auxiliary ignition apparatus for use with an engine ignition system comprising a current source, coil and timer, said auxiliary apparatus including a vibrator coil connected with the current source, and a vibrator controlling electromagnet connected in shunt with the engine ignition primary coil.
14. In combination with an engine ignition system, an auxiliary ignition apparatus comprising a mechanically separate unitary structure including a vibrator coil and an electromagnet for controlling the vibrator, said electromagnet being controlled by the engine ignition system.
15. In combination with an engine ignition system, an auxiliary ignition apparatus comprising a unitary structure including a vibrator coil having a core, and an electromagnet for controlling the vibrator and having a magnetic circuit including the vibrator coil core, said electromagnet being controlled by the engine ignition system.
16. In combination with an engine ignition system, an auxiliary ignition apparatus comprising a housing, an ignition coil mounted within the housing, a coil core extending outside the housing, a vibrator mounted on the housing adjacent the core, and an electromagnet for controlling the vibrator mounted on the housing and having a magnetic circuit including a portion of said core, said electromagnet being controlled by the engine ignition system.

In testimony whereof I hereto affix my signature.

JOHN T. FITZSIMMONS.
